(57) **CLAIM**

The ornamental design for a garden ball, as shown and described.

DESCRIPTION

FIG. 1 is a front perspective view of a garden ball showing my design, the rear side view being a mirror image thereof; FIG. 2 is a front view of FIG. 1, shown without the nets for completeness of illustration, the rear side view being a mirror image thereof;

FIG. 3 is a bottom plan view thereof; and,
FIG. 4 is a top plan view thereof.
